UNITED STATES PATENT OFFICE.

JOHN PRIMROSE, OF RICHMOND, NEW YORK, ASSIGNOR TO FOSTER WHEELER CORPORATION, OF NEW YORK, N. Y., A CORPORATION OF NEW YORK.

RETURN TUBULAR SUPERHEATER BOILER.

Application filed January 29, 1923. Serial No. 615,636.

The general object of my invention is to provide a boiler furnace of the return tubular type with a superheater so arranged and disposed as to obtain the desired superheating effect, with a superheater which is simple, effective, accessible, and relatively inexpensive in construction; and which is so disposed as to minimize the construction and maintenance cost of the furnace housing. These results I 10 secure, in accordance with the present invention, by utilizing a superheater of the radiant heat type, as a roof for the portion of the furnace chamber at the rear of the boiler proper.

15 The various features of novelty which characterize my invention are pointed out with particularity in the claims annexed to and forming a part of this specification, but for a better understanding of the invention, its 20 advantages and specific objects attained with its use, reference should be had to the accompanying drawings and descriptive matter in which I have illustrated and described preferred embodiments of my invention.

25 Of the drawings:

Fig. 1 is an elevation, in section on the line 1—1 of Fig. 3;

Fig. 2 is a view taken similarly to Fig. 1, but 30 on a larger scale, and showing a portion only of the apparatus shown in Fig. 1;

Fig. 3 is a section on the line 3—3 of Fig. 1;

Fig. 4 is a partial section on the line 4—4 of Fig. 5; and

Fig. 5 is a view taken similarly to Fig. 3 35 illustrating a portion of a modified construction.

In the drawings, and referring first to the construction shown in Figs. 1, 2 and 3, A represents boiler of the horizontal return tubular 40 type, and B and B' represent the masonry side and rear end walls, respectively, of the furnace housing which encloses the combustion chamber space C beneath the boiler A proper, and the portion C' of the furnace 45 chamber at the rear of the boiler, through which the products of combustion and burning gases pass from the combustion space beneath the boiler into the boiler flues A'. The boiler proper may be suspended, or may be 50 supported by the boiler housing in any usual or suitable manner. The boilers shown in Figs. 1, 2 and 3 may be heated by the combustion of coal on a grate, or by the combustion of oil or gas, and as shown, was designed 55 for the combustion of oil, but I have not

thought it necessary to show the oil burners and supply provisions, as my invention is not concerned with the character of fuel burned, or with the provisions made for its combustion.

The roof of the chamber portion C' is formed in large part by a superheater D. The superheater D comprises superheater tubes D' proper, each having a horizontal body portion terminating at one end in a bent 60 upturned portion D² connected to the superheater inlet header D³. At its opposite end, each superheater tube D' is connected to the superheater outlet headers D⁴. The body portion of each tube D' is surrounded by a 65 tubular casing formed of cast iron sections D⁵ which may be shrunk on the tubes, and have vertical sides and horizontal under surfaces. The tubes D' and casing sections D⁵ are so relatively proportioned and spaced that 70 the various sections D⁵ form a sectional wall or roof, the under surface of which is horizontal. The body portions of the tubes D' are prevented from warping or bending under 75 the changing temperature conditions to which 80 they are subjected by stiffening members in the form of angle bars E arranged, one above each tube D', and bolted or otherwise secured to the casing sections D⁵ on the corresponding tube D', at suitable intervals D⁶ along the 85 length of the tube. The superheater proper is covered by a suitable heat insulating material G, such as the mortar like material known as plastic asbestos, which preferably 90 not only restricts heat loss by radiation from the top of the superheater, but serves as a packing or casing to prevent air and gas leakage through the joints in the superheater structure. As shown, the boiler proper has 95 its upper side covered by heat insulating material G'.

The superheater, as a whole, is supported from the side walls B of the furnace housing, through the superheater headers D³ and D⁴ which are preferably anchored in place on 100 those side walls. In the particular construction illustrated, each header is supported adjacent its ends, by a saddle or bearing block H which rests upon the corresponding side wall B and is secured to the latter by 105 anchor bolts I. Preferably each saddle block or bearing member H is provided with apertured ears to receive the ends of a yoke J for clamping the header in place. While the end tube casing sections D⁵ are shown 110

as in close contact with the housing side walls B, the weight of the superheater tubes and casings is intended to be wholly carried by the headers D³ and D⁴. With the super-
 5 heater tubes D' and casings D⁵ suspended from the headers D³ and D⁴, the elongation and contraction of the body portions of the tubes, resulting from their changes in tem-
 10 perature are accommodated by flexure of the end portions D², and may occur without liability of damage to the superheater or furnace housing walls B, B, as a result of resistance offered by the latter to relative movement between the tubes and housing
 15 walls. Steam passes to the header D³ from the steam dome A² of the boiler, through the steam pipe F. In Figs. 1, 2 and 3, the width of the superheater is a little less than the depth of the furnace chamber portion C'.
 20 and the rear wall of the furnace housing is corbelled, as indicated at B² to close the space between the rear edge of the superheater and the inner surface of the wall D'. In many cases, however, the superheater may
 25 be of the same width, or of even greater width than the depth of the furnace portion chamber C', as shown in Fig. 4.

With the described arrangement shown in Figs. 1, 2 and 3, the superheater receives
 30 heat by radiation from the adjacent inner surfaces of the furnace walls, and in addition receives heat by contact with, and radiation from the heating gases. The heat absorbing capacity of a superheater thus constructed and located, is sufficient to obtain any superheating effect ordinarily desired in practice, with a superheater which is durable, relatively small in bulk, comparatively inexpensive to construct, and is readily accessible for inspection and repairs when necessary. The fact that the superheater forms
 35 the roof of the furnace chamber portion C' simplifies and cheapens the cost of construction of the boiler housing, and lowers the furnace housing maintenance cost, inasmuch as the superheater replaces the arched roof for the furnace chamber portion C' of the ordinary return tubular boiler furnace which has been a relatively expensive portion of
 40 the boiler housing to construct, and has required frequent repairs and renewal because of its form and the severe temperature conditions to which it is subjected. The superheater construction and arrangement not only reduces the maintenance cost of the boiler housing by eliminating the necessity of repairing and renewing the roof formed by the superheater, but also because the superheater absorbs heat by radiation from
 45 the adjacent side walls B, and from the end wall B', and thereby cools and makes more durable, those portions of the furnace wall.

Heretofore in a return tubular boiler pro-
 50 vided with a superheater, the regular prac-

tice has been to arrange the superheater in the combustion chamber so that the superheater tubes are swept by the heating gases and receive heat mainly by convection and conduction. In comparison with such an arrangement, the present invention possesses advantages in addition to those already mentioned in that it does not obstruct any part of the combustion chamber, as do the tubes of a superheater disposed in the chamber, and consequently does not interfere with any desired disposition of the boiler blow-off piping, and does not interfere with the inspection, cleaning, or repair of the boiler and particularly of the boiler flues. With the present invention, moreover, it is much easier to keep the superheater clean than with the old arrangement, both because the new superheater is easier to clean, and also because soot and ashes accumulate on it much more slowly than they do on the superheater in the old arrangement. With the superheater forming a part of the furnace housing wall, the heat radiation losses from the housing are reduced.

In the modified construction shown in Figs. 4 and 5, the superheater DA shown, differs from the superheater D first described principally in that the superheater tubes D¹⁰ are each provided with a bent upturned end portion D¹¹ at each end, so that the inlet and outlet header D¹² and D¹³ may be symmetrically disposed at the same level. While the tube end portions D¹¹ are shown as passing through the upper portion of the side walls B of the furnace housing, the weight of the superheater as a whole is carried through the headers D¹² and D¹³, and sufficient clearance should be provided between the masonry and the tube end portions D¹¹, to accommodate the thermal elongation and contraction of the body portions of the superheater tubes. In Figs. 4 and 5, the inlet header D¹² receives steam through the steam pipe FA connected to one end of the boiler AA.

While in accordance with the provisions of the statutes, I have illustrated and described the best forms of my invention now known to me, it will be apparent to those skilled in the art that some changes in form may be made without departing from the spirit of my invention as set forth in the appended claims, and that some features of my invention may sometimes be used to advantage without a corresponding use of other features.

Having now described my invention, what I claim as new, and desire to secure by Letters Patent, is:

1. In a return tubular boiler furnace having masonry housing walls at the sides and rear end of the furnace chamber portion at the rear of the boiler, the improvement which consists in a superheater forming a roof for said chamber portion and comprising headers mounted on the housing walls at the sides

of said chamber portion, and superheater elements connecting said headers and each comprising a body portion extending across said chamber portion and a transverse end portion 5 connecting the body portion to one of said headers.

2. In a return tubular boiler furnace having housing walls at the sides and rear end of the portion of the furnace chamber at the 10 rear of the boiler, the improvement which consists in a superheater forming a roof for said chamber portion and comprising headers mounted on the housing wall at the sides of said chamber portion, and tubes each comprising 15 a body portion extending across said chamber portion and up-turned end portions connected to said headers.

3. In a return tubular boiler furnace having masonry housing walls at the sides and 20 rear end of the portion of the furnace chamber at the rear of the boiler, the improvement which consists in a superheater forming a roof for said chamber portion and comprising headers mounted on the housing walls at 25 the sides of said chamber portion, super-

heater elements connecting said headers and each comprising a body portion extending across said chamber portion and a transverse end portion connecting the body portion to one of said headers and means for 30 securing each of said headers in position on said wall comprising a bearing member mounted on said wall and a yoke clamping the header in position on said bearing member. 35

4. In a return tubular boiler furnace having housing walls at the sides and rear end of the portion of the furnace chamber at the rear of the boiler, the improvement which consists in a superheater forming a roof for 40 said chamber portion and comprising headers mounted on the housing wall at the sides of said chamber portion, and tubes each comprising a body portion extending across said chamber portion and having their extremities 45 connected to said headers.

Signed at New York, in the county of New York and State of New York, this 26th day of January, A. D. 1923.

JOHN PRIMROSE.
